UNITED STATES PATENT OFFICE.

JOHN F. CHRISTIN, OF CHICAGO, ILLINOIS.

BOTTLE-HOLDING DEVICE.

SPECIFICATION forming part of Letters Patent No. 773,475, dated October 25, 1904.

Application filed January 22, 1904. Serial No. 190,157. (No model.)

To all whom it may concern:

Be it known that I, JOHN F. CHRISTIN, a citizen of the United States, residing at Chicago, in the county of Cook and State of Illinois, have 5 invented certain new and useful Improvements in Bottle-Holding Devices, of which the following is a specification.

The bottle-holder of this invention is intended for use more especially in connection with 10 soda-water fountains for the purpose of enabling the operator to bottle carbonated beverages at the fountain; and the object of the invention is to provide a readily-adjustable bottle-holder which can be quickly and easily 15 applied to or removed from the sealing-head, which bottle-holder will be adapted for the holding of bottles of varying size and at the same time will be so arranged that the bottle when once inserted into place can be quickly 20 and tightly forced against the sealing-head to establish the seal and enable the carbonated water to be drawn into the bottle.

The invention consists in the features of construction and combinations of parts hereinabove 25 described and claimed.

In the drawings illustrating the invention, Figure 1 is a side elevation of an ordinary sealing device having the bottle-holder of the present invention attached thereto; Fig. 2, a side elevation of the bottle-holder, and Fig. 3 a cross-sectional view of the same.

As shown in Fig. 1, the device is applied to a filling-head A of the kind ordinarily employed in bottling carbonated beverages and 35 adapted to be secured to a soda-water tank, said head having a slidable rod a extending therethrough, which rod is operated by means of a lever B, pivoted to the rod a by means of a pivot b, and said lever is provided on one 40 end by a handle C and has its other end pivoted to a link c, which latter in turn is pivoted to a fixed arm c', outwardly projecting from the filling-head. The rod a is provided on its lower end with a hook c² for the purpose 45 of sealing the stopper in the bottle after the carbonated water has been admitted thereto.

The sealing-head is provided with two oppositely-disposed outwardly-projecting arms 50 D, by which the bottle-holder of the present

invention is supported. The bottle-holder itself consists of two supporting rods or bars d, suitably spaced for the insertion of a bottle and of a length to support bottles of varying size, said supporting-rods being provided 55 at their upper end with curved portions d', adapted to hook over the outwardly-projecting arms D, and said curved portions or hooks are adapted to quickly and easily slip over the laterally-projecting arms. To said rods is attached 60 a base plate or disk E, through which is screw-threaded a stud e, supporting a platform e', which serves as a base or rest for the bottle to be inserted into the holder. The screw-threaded stud e is provided on its lower 65 or outer end with an adjusting-wheel e², which enables the platform to be raised or lowered in order to adapt the holder for use with bottles of varying lengths. The two arms are held distended by means of a curved brace e³, 70 which is attached to the supporting-rods at a suitable distance from their base and is curved to conform to the curvature of a bottle.

In use when it is intended to bottle carbonated beverages at a soda-fountain a sealing-head of the character indicated is substituted 75 for the faucet ordinarily employed and the bottle-holder of the present invention is inserted into place by hooking the supporting-rods over the projecting arms on the sealing-head, and a bottle is then inserted into place 80 on the platform, after which said platform may be screwed up, thereby forcing the mouth of the bottle into the sealing-head and at the same time holding the supporting-rods in rigid 85 contact with the laterally-projecting rods on the sealing-head, and the action of the screw-threaded stud tends at the same time to force the bottle up and draw the rods down at one 90 operation.

It will be seen that the bottle-holder of the present invention is simple in construction and of a character to be easily attached to and removed from a sealing-head and that it enables the operator to bottle his goods directly 95 at the soda-fountain, if so desired, without the necessity for buying goods already bottled, thereby obviating the necessity of keeping a large supply of bottled goods in stock. Although the present invention has been de- 100

scribed in connection with a seal adapted for use in connection with soda-fountains, it is obvious that it may be readily attached to sealing-heads of any ordinary character.

5 What I regard as new, and desire to secure by Letters Patent, is—

1. In combination with a sealing - head adapted to be attached to a soda-water tank and having a slidable hooked rod extending therethrough, a bottle-holder having supporting-rods adapted to be removably secured to the sealing-head, a base to which the supporting-rods are rigidly attached, a support for a bottle, and a screw-threaded stud for upwardly projecting the bottle-support, substantially as described.

15 2. In combination with a sealing - head adapted to be removably secured to a soda-

water tank and provided with a slidable hooked rod extending therethrough, and arms outwardly projecting therefrom, a bottle-holder provided with rods adapted to be hooked onto the outwardly-projecting arms, a base to which the rods are rigidly secured, a platform between the arms, and a screw-threaded stud attached to the platform and projecting through the base for upwardly projecting the platform to force the mouth of a bottle into the slotted head and hold the supporting-arms rigidly onto the outwardly-extending arms, substantially as described.

JOHN F. CHRISTIN.
